LOOM TEMPLE

Frank A. Hoffman, Waverly, Pa., assignor to
 Collins Supply and Equipment Company,
 Scranton, Pa., a copartnership

Application May 15, 1950, Serial No. 161,965

8 Claims. (Cl. 139—296)

1

This invention relates to improvements in temples for looms.

Certain temples heretofore conventionally used included a plurality of guiding or pressure rollers so positioned that the cloth traveling over or under these rollers was distorted longitudinally by the rollers or the rollers and lips which constitute and apply the pressure required to hold the web in position. While these prior art devices could, by sufficiently tight gripping of the selvage and adjacent cloth, be made to hold the cloth to its full width, the necessarily tight gripping of the cloth between adjacent offset rollers or lips inevitably resulted in imparting a permanent elongation to the selvage and adjacent area of the cloth so that the affected edges of the web were rippled or waved. So serious has been this condition that it has been conventional to after-treat the woven web by subjecting the same to controlled stretching or distortion in the part intermediate the selvage and adjacent areas in an attempt to neutralize the selvage distortion.

A primary object of the invention is to provide a loom temple which shall effect any desired transverse holding of the cloth web without, however, to any degree longitudinally distorting, e.g., waving or rippling, the selvage or selvage-adjacent areas of the cloth. Other inventive objects will be apparent from a consideration of the following description.

The loom temple of the present invention is characterized by the combination of a friction-surfaced flexible belt supported on a pair of spaced generally parallel rollers, a generally flat bed plate, the latter co-operating with the belt to bear on opposite sides of a selvage portion of a web of cloth being woven on a loom, means for urging the belt—preferably a substantial area of belt—toward the bed plate under a controlled predetermined pressure, and means for maintaining the belt rollers and therefore the belt at a desired angle with respect to such web, that is to say the axis of the belt is maintained outwardly oblique to the longitudinal axis of a web of cloth being woven on such loom in the direction of travel of the web. The belt may be and preferably is urged toward the bed plate by a pressure shoe riding on the inner surface of the belt and—in conjunction with pressure-applying means—functioning to flex the belt outwardly toward the bed plate and hence to effect gripping of a web between belt and bed plate. Two such temples, right and left hand complements of each other, are secured on the loom frame to

2

grip the right and left hand selvages, respectively, of the web. As the web is drawn forward, it rotates the belts, and the latter, by reason of their frictional engagement of substantial areas of the same with the web and by reason of their angularity with respect to the web, exert laterally outward forces on the web tending to hold the latter to its full width but without any crimping or distorting of the selvages. The outwardly applied force may be varied by adjusting the degree of angularity of the temples. Holding pressure may be increased by adjusting the amount of pressure by which the pressure shoe is forced against the belt.

Specifically, the preferred form of the temple of the present invention comprises a friction-surfaced flexible belt trained over a pair of substantially horizontally disposed parallel spaced rollers carrying belt-guiding end flanges and having trunnions on their ends; a pressure shoe, at least coextensive in length with the width of the belt and of substantial width, disposed between the spaced rollers and supported on the inner surface of the lower flight of said belt, said pressure shoe having at the outer end thereof a depending lip engaging the outer edge of said belt and constituting a guide for the latter, and having a pair of recesses in its upper inner and outer end surfaces to receive the lower ends of force-applying pin members, said pressure shoe being adapted to transmit a force against said belt to flex the latter downwardly; a bracket carrying an outwardly extending bed plate disposed adjacent said pressure shoe, said bed plate presenting an essentially plane and smooth face, at least coextensive in width and length with said pressure shoe, in opposition to the lower flight of said belt and to the belt-engaging surface of said pressure shoe, said bracket having an end portion extending beyond said bed plate which end portion is provided with a pair of spaced horizontally extending parallel bores or cylindrical recesses constituting bearings for inner end trunnions of the pair of belt-supporting rollers and with a central recess, intermediate said spaced recesses, adapted to receive the inner end of said pressure shoe and to provide for the latter a guideway permitting limited vertical movement of the same therein, said bracket being provided also with a centrally located vertically disposed aperture or bore, in alignment with the recess in the inner upper end surface of said pressure shoe, to accommodate a force-applying pin member; a housing mounted at its inner end on and secured to said bracket at the end portion

of the latter, said housing having a key and keyway connection with said bracket and being at least coextensive in length with the width of said belt, said housing having at its outer end a pair of spaced depending portions in the form of jaws or guides which latter are provided with a pair of spaced adjustable bearing members for engaging the outer end trunnions of said belt-supporting rollers and which define therebetween a centrally disposed recess adapted to receive the outer end of said pressure shoe and to constitute for the latter a guideway permitting limited vertical movement of the same therein, said housing being provided adjacent its inner and outer ends with vertically disposed openings or bores, in alignment with the aforesaid recesses in the upper inner and outer end surfaces of said pressure shoe, to accommodate a pair of force-applying pin members; an upstanding post centrally located and carried on the housing, a U-shaped yoke member having a centrally located aperture adapted to accommodate said upstanding post, the ends of said yoke member being a pair of depending force-applying pins adapted to enter the recesses in the upper inner and outer end surfaces of said pressure shoe; a compression spring bearing against the yoke member adjacent said central aperture therein; a lock nut cooperating with said post to maintain said compression spring under compression against said yoke member; an off-standing lug on said bracket; a bracket arm provided adjacent one end thereof with a pivotal connection with said bracket lug and, adjacent the other end thereof, with means for attachment to a holder attached to the loom frame, and means for maintaining the temple at any desired angle with respect to the fabric web being woven.

The invention will now be described in greater particularity, with reference to the appended drawing, in which:

Fig. 1 is a plan view showing a complementary pair of temples mounted in a suitable temple-supporting means carried on the loom frame, and gripping the selvages and selvage-adjacent areas of a fabric web being woven thereon;

Fig. 2 is a top plan view of the left-hand temple shown in Fig. 1, minus its bracket arm, and drawn to an enlarged scale;

Fig. 3 is a side elevation view of the temple shown in Fig. 2;

Fig. 4 is a sectional view taken along line 4, 4 of Fig. 3, with a portion of the belt broken away to show the pressure shoe member;

Fig. 5 is an end elevation view of the temple shown in Figs. 2, 3 and 4;

Fig. 6 is a vertical section taken on line 6, 6 of Fig. 5;

Fig. 7 is a top plan view of the bracket member of the temple;

Fig. 8 is an end elevation of the bracket of Fig. 7;

Fig. 9 is a bottom plan view of the housing member of the temple; and

Fig. 10 is an end elevation of the housing of Fig. 9.

In the drawing, the friction surfaced flexible belt 10 of the left hand temple T₁ may be and preferably is an endless rubber web of substantial thickness, which belt is trained over a pair of belt-supporting rollers 11, 12. Roller 11 is provided with belt-guiding end flanges 13, 14, and trunnions 17, 18, and roller 12 likewise is provided with end flanges 15, 16 and trunnions 19, 20. The pressure shoe 21, which is rigidly

supported on the inner surface of the lower flight of belt 10 between rollers 11, 12, is longer than belt 10 is wide and its end portions 22, 23 extend beyond the belt; in these end portions are provided recesses 24, 25 to receive ends of pins 26, 27. From the outer end 23 of pressure shoe 21 depends a lip 28 constituting a guide for the outer edge of belt 10.

As clearly shown in Figs. 6-8, bracket 29 includes at the left side thereof a centrally located rectangular recess 30 constituting a vertical guideway for the associated end 22 of pressure shoe 21, and a pair of spaced horizontally extending recesses 31, 32 defining bearings for the trunnions 17, 19 of rollers 11, 12. Also formed integrally with bracket 29 is a horizontally disposed substantially rectangular bed plate 33 having a plane and polished upper face against which the underside of the web is pressed by belt 10. If desired, the end and side edges of the bed plate are smoothly rounded off as at 33a, to eliminate possibility of damage to the web.

The top face of the bracket 29 is provided with a keyway 34.

Housing 35 includes an inner end portion 36 the under surface of which is provided with a key 37, complementary with keyway 34 of the bracket, and an outer end portion 38 from which depend two jaws or guides 39, 40, whose parallel inner surfaces 39a, 40a, in part define a recess or guideway 35a for the outer end 23 of pressure shoe 21, permitting limited vertical movement of the pressure shoe therein. The inner and outer ends of housing 35 are provided with bores or openings 41, 42, adapted to accommodate pins 26, 27. Housing 35 is secured to bracket 29 by means of stud bolts 43, 44, which pass through housing 35 by way of bores or openings 45, 46 and thread into threaded bores 47, 48 provided in bracket 29.

Screw threaded into the jaws 39, 40 respectively at the outer end of the housing are bearing inserts 49, 50 provided with axial bores 51, 52 for receiving the trunnions 18, 20 of rollers 11, 12. The heads of these inserts are slotted, as shown at 53, to permit axial adjustment of the bearings with respect to the rollers.

An upstanding post 54, having its upper end threaded as indicated at 55 is fixed to housing 35, by means of a threaded connection 56 within a boss 57, as shown, centrally with respect to pressure shoe 21.

Yoke member 58, from which depend pins 26 and 27, is provided with a centrally located aperture 59 adapted to accommodate post 54. Compression spring 60 bears against yoke member 58 adjacent aperture 59 therein and is held under compression by means of washer 61, adjustment nut 62 and lock nut 63.

As shown in Figs. 1 and 5 in particular, the temple is supported on the loom by means of a resilient temple holder 64 of conventional construction, which temple holder per se forms no part of this invention. An arm 65 extends rearwardly from the temple holder with respect to the direction of movement of the web. The outer end of arm 65 terminates in a bored lug 66 in alignment with a bored lug 67 on bracket 29, the two lugs being secured together by means of a through bolt 68. The contacting faces of lugs 66 and 67 may each be provided with radially extending serrations 69 to better insure maintenance of the temple at the desired angular relation with respect to the web.

The right hand temple T₂ is structurally identical with the left hand temple T₁ except that it

is the mirror image of the latter, and for such reason is not described in detail.

In use, the desired angularity of temples T_1 T_2 is effected by suitable settings of the pivotal connections between the same and arms 65 , and the desired degree of gripping of the web between belts 10 and bed plates 33 is effected by suitable adjustments of the compressions under which springs 60 are maintained. As the web is drawn forward it rotates the belts. Because the belt axis 10 of each temple is so disposed as to lie outwardly oblique at an angle α with respect to the axis 71 of the web in the direction of travel of the web, as depicted in Fig. 1, the belts exert outwardly directed forces on the web tending to maintain the latter at its full width.

I claim:

1. A loom temple comprising in combination a friction-surfaced flexible endless belt, spaced roller means supporting the belt, a generally plane-faced bed plate, means for forcing a substantial area of the belt against the bed plate and means for maintaining the belt axis outwardly oblique with respect to the axis of a web of cloth being woven in the direction of travel of said web, a selvage portion of which is passed between said belt and bed plate.

2. A loom temple comprising in combination a friction-surfaced flexible endless belt, spaced roller means supporting the belt, a generally plane-faced bed plate, the bed plate and belt co-operating to bear on opposite sides of a selvage portion of a web of cloth being woven, a pressure shoe riding on the inner surface of the belt, means for forcing the pressure shoe against the belt toward the bed plate, and means for maintaining the belt axis outwardly oblique with respect to the axis of said web in the direction of travel of such web.

3. A loom temple comprising in combination a friction-surfaced flexible endless belt, a pair of spaced parallel rollers supporting the belt, a generally plane-faced bed plate, substantial areas of the bed plate and belt co-operating to bear on opposite sides of a selvage portion of a web of cloth being woven, a pressure shoe disposed between the spaced rollers and riding on the inner surface of the belt, means for forcing the pressure shoe against the belt towards the bed plate, and means for maintaining the belt axis outwardly oblique with respect to the axis of said web in the direction of travel of such web.

4. The loom temple defined in claim 3, in which the pressure shoe is longer than the belt is wide and its ends extend beyond said belt, and in which said pressure shoe forcing means includes a U-shaped yoke member the ends of which constitute a pair of generally parallel pressure-applying pins straddling said belt and bearing on opposite ends of that face of said pressure shoe which is remote from said bed plate, a compression spring bearing at one end thereof on said yoke member and means, adjacent the opposite end of said spring, for maintaining the spring under a controlled compression against said yoke member.

5. The loom temple defined in claim 4, in which the bed plate constitutes a part of a bracket member which bracket member is provided with bearings for the inner ends of said rollers, in which a housing member longer than said belt is wide is secured to said bracket and extends across said belt generally parallel to said bed plate, said housing member at that end thereof which is remote from said bracket being provided with bearings for the outer ends of said rollers, and in which the spring compressing means is carried on said housing member.

6. The loom temple defined in claim 5, in which the rollers are provided with end flanges constituting guides for the opposite edges of the belt, and in which the pressure shoe is provided, at that end thereof remote from the junction of the bracket with the housing, with a depending lip constituting a guide for the belt intermediate the adjacent roller flanges.

7. The loom temple defined in claim 6, in which the bracket is provided with a substantially horizontally disposed recess into which recess the inner end of said pressure shoe extends, and in which that end of said housing which is remote from the junction of the housing with the bracket includes a pair of depending terminal portions, in which terminal portions said bearings for the outer ends of the rollers are provided, said spaced terminal portions having their opposed faces generally parallel and in part defining a recess into which recess the outer end of said pressure shoe extends, said recesses constituting guideways for said pressure shoe permitting limited vertical movement while restraining sidewise movement of said pressure shoe.

8. The loom temple defined in claim 7, in which the face of said pressure shoe which is remote from the bed plate is provided with a pair of generally vertical recesses one in each of the ends of said pressure shoe extending beyond said belt, in which said bracket and said housing are provided with generally vertical apertures registering respectively with the said recesses in said pressure shoe, and in which the pin ends of said yoke member pass through said apertures and are engaged in the said recesses in said pressure shoe thereby restraining the pressure shoe against endwise dislodgment.
